[57] ABSTRACT

Three yarns are knit in plied relationship throughout the major portion of at least the leg of the sock with the first of the yarns being positioned predominantly on the outside, the third of the yarns being positioned predominantly on the inside and the second of the yarns being normally positioned between the first and third yarns but appearing on the outer surface of the sock in portions of irregularly spaced stitch loops to provide a variegated pattern resembling denim. The second yarn is of a different color than the first yarn and is approximately one and one-half times as large as the first yarn while the third yarn is approximately twice as large as the second yarn. The tension and feeding positions of the three yarns are controlled to maintain the three yarns in plied relationship with the first yarn on top of the second yarn but the relatively thin or smaller first yarn will not always stay on top of the larger second yarn so that the second yarn is irregularly exposed as it moves from one side to the other of the smaller first yarn to produce the variegated pattern resembling denim.

PATENTED AUG 13 1974

3,828,585

DENIM SOCK AND METHOD OF KNITTING SAME

This invention relates generally to a sock having a variegated pattern resembling denim on the outer surface and to the method of producing the sock on a circular knitting machine.

It is well known to produce various types of patterns by knitting one yarn in plated relationship with another yarn of a different color. However, these known patterns are of a predetermined design or configuration and the yarn which is positioned on the outside of the knit sock is determined by changing the feeding position of the yarns, changing the tension on the yarns, and/or changing the movement of the sinkers relative to the feeding position of the yarns.

In contrast to the known methods of plating yarns, it is an object of the present invention to produce a denim sock knit with three yarns and wherein the tension and feeding positions of the yarns are maintained the same during the knitting of the sock but the relative plated positions of the first and second yarns change in portions of irregularly spaced stitch loops to provide a variegated pattern which resembles denim.

In accordance with the present invention, the second yarn is of a different color than the first yarn and the second yarn is approximately one and one-half times as large as the first yarn while the third yarn is approximately twice as large as the second yarn. Although the knitting conditions are maintained to normally plate the first yarn on the outside of the sock to hide and cover the second yarn, the larger second yarn is occasionally moved from one side to the other of the smaller first yarn so that it is exposed on the outer surface of the sock and in irregularly spaced stitch loops to produce the variegated pattern resembling denim.

Other objects and advantages of the present invention will appear as the description proceeds, when taken in connection with the accompanying drawings, in which

FIG. 1 is a side elevational view of the denim sock of the present invention;

FIG. 2 is a greatly enlarged fragmentary portion of the fabric in the leg of the sock, illustrating the manner in which the yarns are plated together in the stitch loops of the sock; and

FIG. 3 is a fragmentary isometric view of the yarn feeding throat of a circular knitting machine and illustrating the manner in which the three yarns are fed to the needles for knitting.

The sock of the present invention may be knit of any desired length and may be provided with an upper ribbed cuff 10, a leg 11, a heel pocket 12, a toe pocket 13, and a foot including a lower sole portion 14 and an upper instep portion 15. A high splice area 16 may be provided in the area above the heel pocket 12 and terry loops may be formed on the inner surface in the high spliced area 16, the heel 12, the sole portion 14 and the toe pocket 13.

As illustrated in FIG. 2, three yarns are knit throughout the major portion of at least the leg of the sock. The first of the yarns, indicated at Y-1 and being speckled for ease of identification, is positioned predominantly on the outside of the sock. The second yarn, indicated at Y-2 and being left plain, is normally plated beneath the first yarn Y-1. The third yarn, indicated at Y-3 and being striped, is positioned predominantly on the inside of the sock and is plated beneath the first and second

yarns Y-1 and Y-2. However, in accordance with the present invention, the second yarn Y-2 appears on the outer surface of the sock in irregularly spaced stitch loops to provide a variegated pattern resembling denim on the outer surface of the sock.

The sock of the present invention may be knit of various types, sizes and colors of yarns, however, it has been found necessary that the second yarn be larger than the first yarn in order to produce the desired denim appearance. It has been found that a particularly attractive denim appearance can be produced by utilizing a textured nylon 100/2 denier yarn Y-1, a 16/1 cotton yarn Y-2 and a bulked orlon 2/24 yarn Y-3. The size of the cotton yarn is given as the count under the 10 cotton system while the size of the orlon yarn is given as the count under the worsted system. Comparing the two yarns Y-2 and Y-3 to the denier of the yarn Y-1, the yarn Y-1 has a total denier of 200, the yarn Y-2 has a total denier of 332 and the yarn Y-3 has a total denier of 664 denier. Thus, the second yarn Y-2 is approximately one and one-half times as large as the first yarn Y-1 while the third yarn Y-3 is twice as large as the second yarn Y-2. The textured nylon yarn Y-1 may be of any desired color and is preferably of the same color as the bulked yarn Y-3 while the cotton yarn Y-2 is white to produce the denier appearance when it is exposed in an irregular manner on the outer surface of the sock.

METHOD

The sock of the present invention is preferably knit on a circular hosiery knitting machine and the tension and feeding position of the yarn Y-3 is controlled so that the third yarn is knit predominantly on the inside of the sock while the tension and feeding position of the first yarn Y-1 is controlled so that this yarn is normally knit on the outside of the sock. The tension and feeding position of the second yarn Y-2 is controlled to normally knit between the first and third yarns while the second yarn is permitted to knit on the outer surface of portions of irregularly spaced stitch loops to provide the variegated pattern resembling denim on the outer surface of the sock.

The manner of feeding the yarns to the needles N of the knitting machine is illustrated in FIG. 3 wherein a fragmentary portion of the latch ring 20 of the knitting machine is illustrated. A yarn feed throat 21 is provided in the latch ring 20 and yarn feed fingers 22, 23 are supported for movement into and out of yarn feeding position in the throat 21. The first yarn Y-1 and the second yarn Y-2 are fed through the same yarn feed finger 22. The yarns Y-1 and Y-2 are fed through adjacent openings in the finger 22 and downwardly through a tubular extension which passes through an opening in the throat 21 so that both yarns are fed to the needles at a low level, just above the stitch forming ledge and in front of the nebs of the sinkers, not shown. The third yarn Y-3 is fed through the yarn feed finger 23 which has a wide yarn opening at its inner end so that the feeding position of the third yarn may switch from one side to the other when the needles reciprocate, during the knitting of the heel and toe pockets. The third yarn Y-3 is fed at the level of the throat 21 and at a higher level than the yarns Y-1 and Y-2.

As the yarns are fed to the needles, they pass through conventional types of tensioning devices, not shown, and the greatest amount of tension is maintained on the

yarn Y-1 while a lesser tension is maintained on the yarn Y-2 and the least amount of tension is maintained on the yarn Y-3. The feeding positions and the tension applied to the yarns causes the yarn Y-1 to be fed to the hooks of the needles at an uppermost level, the yarn Y-2 to be fed to the hooks of the needles at an intermediate level, and the yarn Y-3 to be fed to the hooks of the needles at a lowermost level.

The least amount of tension and the lower position in the hooks of the needles causes this third yarn Y-3 to knit predominantly on the inside of the sock as shown in FIG. 2. The lesser amount of tension on the yarn Y-2 and the intermediate position in the hooks of the needles normally dictates that the yarn will knit in plated relationship between the first and third yarns while the greater tension and higher position in the hooks of the needles of the yarn Y-1 dictates that this yarn will normally knit predominantly on the outside of the sock. However, due primarily to the variation in size between the first and second yarns, it is impossible to maintain the smaller yarn Y-1 directly above and on top of the larger yarn Y-2 as the stitch loops are drawn. The yarn Y-2 is at times maintained directly beneath the yarn Y-1 and at other times moves from one side to the other of the yarn Y-1 and is thus exposed on the outer surface in portions of irregularly spaced stitch loops to provide the variegated pattern resembling denim on the outer surface of the sock. At times, the smaller yarn Y-1 does completely cover the larger yarn Y-2, as shown in portions of the stitch loops of wales W-1 through W-4 of course C-1, wales W-1, W-2 and W-3 of course C-2, and wales W-1 and W-4 of course C-3 of FIG. 2. Although this yarn Y-1 is smaller than the Y-2, it expands when not under tension and the individual filaments crimp and curl. While the yarn Y-1 is illustrated as being solid in FIG. 2, the yarn actually is very open as the filaments separate from each other because of the crimp and curl in the individual filaments.

The terry loops are formed in the high splice area 16, the heel pocket 12, the sole portion 14 and the toe pocket 13 by advancing the inward movement of the sinkers, not shown, so that the yarn Y-3 is laid over the nebs, in the well known manner. Since the yarn Y-3 is fed at a higher level than the yarns Y-1 and Y-2 (FIG. 3) there is sufficient separation between the yarns that the nebs of the sinkers may move inwardly above the yarns Y-1 and Y-2 and beneath the yarn Y-3.

In the drawings and specification, there has been set forth a preferred embodiment of the invention, and although specific terms are employed, they are used in a generic and descriptive sense only and not for purposes of limitation.

That which is claimed is:

1. A circular knit seamless sock having a variegated appearance on its outer surface and being knit of at least three yarns, said three yarns being knit in plated relationship and in all the stitch loops throughout the major portion of at least the leg of said sock, the first

of said yarns being positioned predominately on the outside of said sock, the third of said yarns being positioned predominately on the inside of said sock, the second of said yarns being approximately one and one-half times as large as said first yarn and being of a different color than said first yarn, said second yarn normally being positioned between said first and third yarns and normally being hidden by said first yarn, and portions of said second yarn in irregularly spaced stitch loops appearing on the outer surface of said sock to provide a variegated pattern resembling denim on the outer surface thereof.

2. A sock according to claim 1 wherein said first and third yarns are synthetic multifilament textured yarns, and said second yarn is composed of natural fibers.

3. A sock according to claim 1 wherein said third yarn is approximately twice as large as said second yarn.

4. A sock according to claim 1 wherein said first and third yarns are synthetic multifilament textured yarns, said second yarn is composed of natural fiber and is approximately one and one-half times as large as said first yarn, and said third yarn is approximately twice as large as said second yarn.

5. A sock according to claim 1 including a heel pocket, a foot comprising sole and instep portions, and a high splice area above said heel pocket, and including terry loops formed of said third yarn and being formed in said heel pocket.

6. A sock according to claim 5 wherein said terry loops are also formed in said sole portion of said foot and in said high splice area.

7. A sock according to claim 1 wherein said first and third yarns are the same color.

8. A method of knitting a circular seamless sock having a variegated appearance on the outer surface, said method comprising the steps of knitting the major portion of at least the leg of said sock of three yarns in plated relationship while controlling the tension and feeding position of the first of said yarns to normally knit on the outside of said sock, controlling the tension and feeding position of the third of said yarns to knit predominately on the inside of said sock, and controlling the tension and feeding position of the second of said yarns to normally knit between said first and third yarns while permitting said second yarn to be knit on the outer surface of portions of irregularly spaced stitch loops to provide a variegated pattern resembling denim on the outer surface of said sock.

9. A method according to claim 8 wherein the sock is knit on a circular knitting machine having latch needles with hooks on the upper ends thereof, and wherein said third yarn is fed into the hooks of said needles at a lowermost level, said second yarn is fed into the hooks of said needles above the level of said third yarn, and said first yarn is fed into the hooks of said needles above the level of said second yarn.

UNITED STATES PATENT OFFICE
CERTIFICATE OF CORRECTION

Patent No. 3,828,585 Dated August 13, 1974

Inventor(s) James L. Thorneburg

It is certified that error appears in the above-identified patent and that said Letters Patent are hereby corrected as shown below:

IN THE CLAIMS:

Column 4, Line 37, after "knitting", insert --all of the stitch loops in--;

Column 4, Line 39, after "relationship", insert--, the second of said yarns being approximately one and one-half times as large as said first yarn and being of a different color than the first yarn, --.

Signed and sealed this 22nd day of October 1974.
